Attorney.

UNITED STATES PATENT OFFICE.

SWAN ANDERSON, OF MINNEAPOLIS, MINNESOTA.

STEAM-GENERATOR.

1,318,825.

Specification of Letters Patent.

Patented Oct. 14, 1919.

Application filed October 29, 1918. Serial No. 260,112.

To all whom it may concern:

Be it known that I, SWAN ANDERSON, a citizen of the United States, residing at Minneapolis, in the county of Hennepin and State of Minnesota, have invented a new and useful Improvement in Steam-Generators, of which the following is a specification.

The object of this invention is to provide a maximum flue surface in a steam generator whereby water is rapidly and most effectively converted into steam and the pressure of steam maintained under high pressure. A further object is greater economy of fuel in the production of steam and greater simplicity of construction. A still further object is the production of a steam generator in which a constant circulation of water therein is maintained to prevent the incrustation of the flues and the collecting of sediment.

With these and other objects in view my invention comprises the features of construction and combination of parts hereinafter more particularly described and claimed.

In the accompanying drawing forming part of this specification, Figure 1 is a front elevation of my invention, the inclosing structure being broken away and in section to more completely expose the interior of the generator; Fig. 2 is a back elevation of the structure illustrated in Fig. 1, the inclosing casing being broken away and in section; Fig. 3 is a longitudinal section taken on the line X—X of Fig. 1; Fig. 4 is an end view of one of the flues, and Fig. 5 is a side elevation of a detail of one of the flues.

My invention comprises four upright ducts 2, 3, 4, and 5 closed at their lower ends and connected at their upper ends by four transverse ducts 6, 7, 8 and 9, and four double elbows 10, 11, 12 and 13. Arranged across the front pair of vertical ducts 2 and 3 are a vertical series of horizontal tubes or ducts 13', which are substantially straight throughout their lengths, and arranged across the space between the back pair of vertical ducts 4 and 5 are a corresponding vertical series of tubes or ducts 14, each of which is flexed downwardly between its ends. The front and back horizontal series of tubes 13' and 14 are connected by longitudinal tubes 15, there being a plurality of such tubes connected with each horizontal pair of front and back tubes 13' and 14. The tubes at the sides of each horizontal group extend horizontally from front to back, but

the tubes of each group as they approach the center one slant downwardly from the front tube 13' of each horizontal pair to the back tube 14. Each set of tubes 15 is thus arranged in the form of a gutter which extends horizontally at one end and which at the other end inclines downwardly from each side toward the center. As a result a free circulation of water is set up in the assemblage of ducts and tubes described. The heater for heating water in the tubes may be a hydrocarbon burner 16 placed below the tubes in the center of the structure or any other suitable heater desired.

The structure described is inclosed in an outer casing 17, which is insulated by the cover 18 made of asbestos or any other poor heat conducting material. In the top of the casing is a smoke vent or passage 19 and in the lower portion of the casing is a hinged draft door 20. The corner ducts 2, 3, 4 and 5, horizontal ducts 6, 7, 8 and 9 and horizontal tubes 13' and 14 are respectively square in cross section as illustrated in Fig. 4, the ends of the ducts and tubes being rounded for convenience in swaging them into the associated connected elements. The longitudinal tubes 15 are preferably round in cross section and are swaged by their ends into the horizontal tubes 13' and 14. The front and back series of tubes 13' and 14 are of smaller cross sectional area than the vertical ducts 2, 3, 4, and 5 and the longitudinal tubes 15 are smaller in cross sectional area than the tubes of the front and back horizontal series 13' and 14. The entire device presents a maximum heating surface area for generating steam therein and facilitates the conversion of water into dry steam quickly. The upper portion of the corner ducts and horizontal ducts 6, 7, 8 and 9 and elbow elements produce a separating chamber for the steam from the water. Water is preferably fed into the lower portion of the ducts and tubes at any suitable point, that illustrated being by means of the supply pipe 21 connected to the vertical corner duct 3 and steam is conducted from the structure described at the upper portion of the ducts, such as by means of the steam supply pipe 22 connected to one of the horizontal ducts such as 6. In operation water is maintained at a level slightly above the upper set of tubes 15. A water gage 23 is provided by which the depth of water maintained in the structure

can be ascertained from time to time. The entire structure may be made of comparatively small dimensions for generating a maximum quantity of dry steam under high pressure quickly.

The front and back pairs of connected corner ducts constitute a pair of front and back manifolds having front and back sets of cross ducts 13' and 14 to which the front and back ends of exposed tubes 15 are respectively connected, said manifolds forming a water heating structure having a steam separator at the top. This entire structure is so arranged that a maximum heat exposing surface is presented for converting water into steam. A plurality of return hot water conducting transversely arranged tubes 23' are also connected between the upright ducts 2 and 4 and 3 and 5 respectively for facilitating the circulation of water throughout the apparatus.

In accordance with the patent statutes, I have described the principles of operation of my invention together with the apparatus which I now consider to represent the best embodiment thereof, but I desire to have it understood that the construction shown is

only illustrative and that the invention can be carried out by other means and applied to use other than those above set forth within the scope of the following claim.

Having described my invention, what I claim as new and desire to protect by Letters Patent is—

A steam generator comprising four vertical corner ducts, four horizontal ducts connecting said corner ducts at their upper ends, a plurality of straight horizontal ducts connecting one pair of the corner ducts, a plurality of ducts inclined downwardly toward their centers and connecting the other pair of corner ducts, a plurality of tubes connecting each pair of said straight and inclined ducts respectively whereby each set of said tubes is arranged in the form of a gutter which extends horizontally at one end and which at the other end inclines downwardly from each side toward the center, a fire casing inclosing said ducts and tubes, and heating means in said casing beneath said tubes.

In testimony whereof, I have signed my name to this specification.

SWAN ANDERSON.
